UNITED STATES PATENT OFFICE.

LOUIS N. UDELL, OF BOSTON, MASSACHUSETTS.

HEAT EXCHANGER.

Application filed March 26, 1924. Serial No. 701,884.

This invention relates to an improved heat exchanger, and more specifically that type of heat exchanger which serves to transfer heat between two fluids, liquids or gases. 5 My present improvement has been designed more particularly for use in ice-making and other refrigerating machinery, but is capable of application and use broadly in any other arts wherein heat exchangers of the 10 same general type are employed.

One of the present methods of effecting heat exchange is to provide a counterflow or current of the two liquids between which the heat is to be exchanged by means of two 15 pipes, one within the other. This construction is somewhat difficult and expensive to make and assemble, and one object of the present invention is to provide a simple, economical and easily assembled structure 20 which shall function to equal or greater advantage as compared with the two-pipe system. Another object is to provide an improved construction of cooler for taking the heat out of liquids and gases in refrigerating 25 apparatus that will more rapidly and effectively dissipate the abstracted heat than the two-pipe system referred to. A further object is to provide a construction of heat exchanger which will permit of the 30 easy assembling and separation of the two conduits carrying the respective liquids. Other objects and attendant advantages of the invention will be apparent to persons skilled in the art as the same becomes better understood by reference to the following detailed description, taken in connection with the accompanying drawings in which I have illustrated a simple and practical embodiment of the principle of my invention, and wherein—

Fig. 1 is a side elevation of my improved heat exchanger with a portion broken away and in section;

Fig. 2 is an end elevation viewed from the right of Fig. 1, with the tank and one trough in vertical section;

Fig. 3 is a perspective elevation of a fragment of one of the troughs and its supporting bracket.

Referring to the drawings, 10 designates as an entirety each of a group (herein shown as three) of zigzag vertical coils located side by side in close juxtaposition. Underlying alternate limbs of these coils are open troughs 11 and 12. Said troughs are formed 55 with closed ends 11' and 12' respectively,

and with opposite open ends 11^a and 12^a, respectively; the closed end of each trough being somewhat higher than its open end, as clearly shown in Fig. 1, so as to prevent 60 any possibility of lateral overflow of the liquid discharging from the low end of each trough into the high end of the next underlying trough. To permit the troughs to be made of uniform width, the side walls 65 at the closed end of each trough, which receive between them the discharge end of the next underlying trough, are outwardly offset as shown in Fig. 2.

To support the troughs I may employ a 70 series of posts 13 on each of which is mounted a group of supporting brackets properly spaced to seat the several troughs. As clearly shown in Fig. 3, this bracket preferably comprises a collar 14 encircling the post 13 75 and fastened thereto by a set screw 15 or other equivalent means, a bracket plate 16 integral with or attached to the collar 14, and an arm 17 fastened to the bracket plate 16 as by bolts 18 and of sufficient length to 80 span the bottom of the trough and having an upturned end 19 embracing the outer side of the trough. It will be observed that the adjacent limbs of the coils are slightly inclined in opposite directions and that these 85 limbs lie upon and are supported by the bottoms of the troughs. This insures a gravity flow of the cooling liquid from each trough to the next underlying trough in a zigzag course; but the inclination of the troughs is sufficiently slight to make the flow slow 90 enough to always insure the submerging of the limbs of the coils, except their curved end connections, in the cooling liquid.

The top limbs of the several coils are connected by curved pipes 20, preferably of reduced size as shown, into an upper transverse header or manifold 21; and the lower limbs of the coils are connected by straight pipes 22, preferably of reduced size, into a 100 similar header or manifold 23.

For convenience in disposing of the cooling liquid discharged from the lowermost trough, the unit is mounted in a tank T provided with an overflow outlet 24 slightly below the bottom of the lowermost trough.

At 25 is indicated a supply pipe for the cooling liquid provided with a down-turned end or nozzle 25' overhanging the receiving end of the highest trough or pan.

The reduction in size of the pipes 20 and 22 that connect the coils with the upper and

lower headers respectively is not essential but is preferably employed for practical reasons in construction, since making it easier to effect tight connections by welding.

5 It will readily be seen that the troughs or pans 11 and 12 can be withdrawn whenever required for cleaning or repair and then reinserted by a simple endwise movement, without disturbing the coils, and each 10 trough or pan can so be withdrawn entirely independently of the others.

The described apparatus is preferably operated in the counter-current or counter-flow manner, the liquid or gas to be cooled 15 being introduced through the lower manifold 23 under pressure, and being discharged through the upper manifold 21, but manifestly, so far as the structure and its advantages are concerned, the direction of flow is 20 immaterial. The cooling liquid, of course, flows slowly by gravity from top to bottom, flowing from the discharge end of each upper trough or pan into the receiving end of the next underlying trough or pan, 25 and maintaining a continuous submergence of the limbs of the coils. Another advantage of the use of the troughs or pans is that a single trough may be made of sufficient width to embrace the corresponding 30 horizontal limbs of any number of coils placed side by side, thus effecting a considerable economy in construction. Where the system employs a considerable number of coils disposed side by side, the trough 35 supports will preferably take the form of underlying cross-bars supported at their ends by posts on both sides of the coils. It is believed that the foregoing description will make clear to persons skilled in the art 40 the novel structural features, practical economies of construction and maintenance, and other recited advantages of the invention. Manifestly the specific structural details shown and described for purposes of 45 illustration are not of the essence of the invention, but may be variously modified within the skill and judgment of the engineer without involving any departure from the invention or sacrificing any of the advan-

tages thereof. Hence I reserve all such 50 variations and modifications as fall within the spirit and purview of the appended claims.

I claim—

1. In a heat exchanger, the combination 55 of a zigzag coil having its limbs connected by integral bends and disposed in a vertical plane, and two oppositely facing series of endwise removable troughs underlying alternate limbs of the coil respectively and together wholly enclosing the bottoms, sides and ends of said limbs, each trough being closed at its receiving end beyond the bend connecting the limb which it underlies with the next higher limb and open at its discharge end, and the discharge end of each upper trough overlying the receiving end of the next underlying trough.

2. In a heat exchanger, the combination 60 of a zigzag coil disposed in a vertical plane, and two oppositely facing series of inclined troughs underlying alternate limbs of the coil respectively and together wholly enclosing the bottoms, sides and ends of said limbs; each of said troughs having a low 65 open discharge end and a closed high receiving end formed with outwardly offset upward extensions of its side walls between which extensions the open discharge end of the next upper lying trough is entered.

3. In a heat exchanger, the combination of 70 a group of vertical zigzag coils disposed side by side and contiguous with corresponding limbs thereof lying in common transverse planes, two oppositely facing groups of 75 lengthwise removable oppositely inclined troughs underlying alternate groups of limbs of said coils respectively, with the discharge end of each upper trough delivering 80 to the receiving end of the next underlying trough, posts mounted alongside said coils, adjustable brackets on said posts underlying and supporting said troughs, horizontal manifolds disposed crosswise of the opposite 85 ends of the coils, and pipes connecting each 90 manifold into each coil.

LOUIS N. UDELL.
